DESIGN FOR A WATER COOLER OR SIMILAR ARTICLE

James J. Corey, Elmhurst, N. Y.

Application April 12, 1946, Serial No. 128,524

Term of patent 14 years

(Cl. D67—4)

To all whom it may concern:

Be it known that I, James J. Corey, a citizen of the United States and a resident of Elmhurst, in the county of Queens, State of New York, have invented a new, original, and ornamental Design for a Water Cooler or Similar Article, of which the following is a specification, reference being had to the accompanying drawing, forming a part thereof.

In the drawing,

Figure 1 is a perspective view of a water cooler embodying my new design;

Figure 2 is a side elevation of the water cooler of Figure 1; and,

Figure 3 is a top plan view of the water cooler Figure 1.

I claim:

The ornamental design for a water cooler or similar article, substantially as shown.

JAMES J. COREY.
